FUR TRIMMED COAT

Arthur Carew, Sausalito, Calif., assignor to Lilli Ann Corporation, San Francisco, Calif., a corporation of California

Filed May 16, 1968, Ser. No. 11,972

Term of patent 14 years

Int. Cl. D2—01

U.S. Cl. D2—198

FIG. 1

FIG. 2

I claim:

The ornamental design for a fur trimmed coat, as shown.
